BASKET CONSTRUCTION

John M. Wallace, Oakville, Ontario, Canada

Application November 26, 1932
Serial No. 644,434

5 Claims. (Cl. 217—124)

This invention relates to basket constructions and more particularly to improvements in the construction of baskets of the hamper type.

In most types of baskets used for packing 5 fruits, vegetables, and the like, the top or cover member is so secured to the body of the basket that under the rigors of travel the top shifts across the mouth of the basket to a greater or less extent, with the result that fruit or other 10 contents become damaged thereby, such damage being known commonly as "rim-cut".

An object of the present invention is to provide in a basket construction a top or cover which of itself prevents movement of itself across 15 a basket when properly secured thereto.

Another object of the present invention is to provide a cover having the foregoing characteristics, which cover is so constructed as to be capable of use with baskets of conventional character. 20

In accordance with the present invention, a basket is made up in the usual fashion of splints or staves which form preferably both the bottom and sides of the basket, together with hoops for 25 holding the splints in position. More particularly, the basket is formed around its top in such fashion that the ends of the splints terminate substantially flush with the tops of inner and outer hoops. In connection with a basket of this 30 character, use is made of a top or cover member made up of substantially flat strips of material secured to a major or outer hoop member which extends downwardly from one surface of the top. Immediately adjacent to this major hoop member, and inside thereof, is a second hoop member, which preferably is made of material slightly 35 thicker than that of the outside hoop. The second or inside hoop does not extend downwardly from the top members as great a distance as 40 the outside hoop. In addition, use is made of a long slat member extending diametrically across the top to be engaged under the handles secured to the basket part of the device.

The outer and inner hoops of the top member 45 are of such diameter that the outer member fits fairly closely around the outside of the outer hoop of the basket. At the same time, the inner hoop of the cover rests directly against the top of the outer hoop of the basket and also upon 50 the ends of the splints, which are flush with the top of the outer hoop.

Other features, objects and advantages of the present invention will become apparent by reference to the following detailed description taken 55 in connection with the accompanying drawing

forming a part of the same, wherein Fig. 1 is a perspective view of a basket construction embodying the invention.

Fig. 2 is a plan view of a top incorporating the principles of the present invention. 60

Fig. 3 is an enlarged section taken substantially on the line 3—3 of Fig. 2.

Fig. 4 is an enlarged section taken substantially on line 4—4 of Fig. 1. 65

Referring now to the drawing, 10 indicates generally a basket member, while 11 indicates generally a top member associated therewith. The basket portion 10 of the device is made up of a number of splints 12 so shaped as to form the sides of the basket and also the bottom thereof, as is common in this type of construction. Use is made of an outside hoop 13 at the bottom of the device, and an intermediate hoop 14, and a top hoop 15. In conjunction with the top hoop 15, use is made of an inner top hoop 16 between which the ends of the splints 12 are firmly secured by means of fastening members 17. As will be seen by reference to Fig. 4, the tops of the outer and inner hoops 15 and 16 and the ends of the splints 12 lie in substantially a common plane. The purpose of such arrangement will be described in detail hereinafter. 70

The top member 11 of the present invention may be constructed in a number of different ways so far as the slats utilized therein is concerned. In the present illustration, use is made of a pair of slats 20 of such size as to extend almost entirely over the entire area of the top member. In addition, use is made of a slat 21 extending across the two slats 20 and beyond the confines of the top member proper. These two slats 20 are secured by means of fastening members 22 to inner and outer hoops 23 and 24 respectively. 80

The inner hoop 23, as shown in Fig. 3, is thicker than the outer hoop 24, but does not extend downwardly below the slats a distance as great as that of the outer hoop. The inner hoop should be of a thickness at least as great as the combined thicknesses of the outer hoop 15 of the basket, and the splints 12 immediately adjacent thereto. The outer hoop 24 should be of an internal diameter substantially the same as the external diameter of the outer hoop 15 so that this hoop 24 can fit snugly around the outer hoop 15 of the basket. The diameter of the inner hoop 23, of course, should be such as to cause it to fit snugly within the confines of the outer hoop 24. 95

In the use of the present invention, perishable products or other products are packed in the 100 105 110

basket in the usual manner. After the required amount of products have been packed in the basket, the top 11 may be secured in position. This position is shown in the fragmental section 5 of Fig. 4, wherein the outer hoop 24 of the top member fits snugly around the outside of the outer hoop 15 of the basket. At the same time, the bottom edge of the inner hoop 23 rests directly upon the top of this outer hoop 15 and also 10 upon the ends of the splints 12 which are flush with the top of the hoop 15. When so positioned, the top may be secured in place partially by inserting the ends of the slats 21 under handle members 30 secured to the basket in the conventional manner. Other locking means may be employed in conjunction with this arrangement.

With the top so positioned and secured in place, a number of benefits ensue. Since the outer hoop of the top member fits snugly around the outer 20 hoop of the basket member, the chances of the top shifting relative to the basket in such manner as to injure the contents of the basket are substantially eliminated. Any shifting of a basket top across the opening of the basket 25 ordinarily results in the contents of the basket becoming injured by the hoops of the top, which injury is known to the art as "rim-cutting". Furthermore, since the inner hoop of the top member rests not only on the outer hoop of the 30 basket member but also upon the ends of the splints, a considerable part of the strain ordinarily communicated directly to and only to the outer hoop is distributed also to the splints. Due to this arrangement, the possibility of the outer 35 hoop becoming sheared from the basket due to a downward pressure by the top member is substantially eliminated. As shown in the drawing, the inner hoop of the top member is of such thickness as to cause it to rest upon both the outer 40 hoop and the ends of the splints, but at the same time, it does not contact appreciably with the inner hoop of the basket. Of course some variation in thickness of the inner hoop of the top member is permissible, the only requirement being that it shall not be of such thickness as to 45 contact with the contents of the basket. It may be repeated that the minimum thickness of the inner hoop of the top member should be at least as great as the combined thicknesses of the outer 50 hoop of the basket and the splints adjacent thereto.

By having the basket constructed in the manner shown, that is with the tops of the inner and outer hoops and the ends of the splints lying in substantially a common plane, it is possible to use other types of tops with this basket when occasion may permit, but at the same time, the top of the present invention can be used therewith admirably. It follows, therefore, that

60

65

70

675

when the contents to be packed are of such nature that rim cutting thereof will spoil the same, a top of the type shown may be used with the results set forth hereinbefore.

From the foregoing it will be seen that the present invention provides a combined basket and top in which combination the top member is so secured to the basket that shifting of the top member across the top of the basket is substantially prevented, and at the same time, the likelihood of the outer hoop of the basket being sheared off is substantially eliminated. It will be evident, of course, from the foregoing that the invention is capable of considerable modification, since only the preferred form thereof has been illustrated; in view of which it is to be understood that the invention is to be limited not by the illustrated embodiment, but only by the scope of the following claims.

What I claim is:

1. The combination of a basket having inner and outer hoops with splint ends therebetween substantially flush with the tops of the hoops and a cover member having a pair of hoops, one fitting snugly around the outer hoop of the basket 100 and the other resting upon the top of said outer hoop and upon the ends of said splints.

2. The combination of a basket having inner and outer hoops with splint ends therebetween substantially flush with the tops of the hoops and a cover member having a pair of hoops, one fitting snugly around the outer hoop of the basket 105 and the other resting upon the top of said outer hoop and upon the ends of said splints and being of a thickness at least as great as the combined thicknesses of said outer hoop and the splints adjacent thereto.

3. The combination of a basket having inner and outer hoops and splints therebetween, the ends of said splints being substantially flush 115 with the top of said outer hoop, a cover member having a pair of concentric contacting hoops, one of which fits snugly around the outer hoop of said basket and the other of which rests upon the top of said outer hoop and upon the ends 120 of said splints.

4. A top for a basket of the character described comprising a pair of concentric contacting hoops, and slats secured to the top edges of said hoops, the outer hoop being of greater 125 width than the inner hoop.

5. A top for a basket of the character described comprising a pair of concentric contacting hoops, and slats secured to the top edges of said hoops, the outer hoop being of greater 130 width than the inner hoop, and the inner hoop being of greater thickness than the outer hoop.

JOHN M. WALLACE.
